UNITED STATES PATENT OFFICE

ULRICH KOHLER, OF BERN, SWITZERLAND, ASSIGNOR TO HASLER A.-G., VORMALS TELEGRAPHENWERKSTATT VON G. HASLER, OF BERN, SWITZERLAND, A CORPORATION OF SWITZERLAND

ARRESTING AND RELEASING DEVICE OF MACHINES FOR STAMPING POSTAGE ON LETTERS AND THE LIKE

Application filed January 18, 1929, Serial No. 323,389, and in Switzerland January 23, 1928.

This invention relates to an arresting and releasing device of machines for stamping or printing postage on letters or the like, comprising a rotary printing member driven by 5 means of a detachable clutch.

According to an important feature of the invention, a lever that controls the clutch is adjusted or set by the printing member, at each revolution of the latter, in a position for releasing the clutch and stopping the printing member, in which position it is held by a locking member that can be set in 10 its releasing position by means of an article to be printed, and is automatically returned 15 into its locking position by the said lever when the clutch is being disengaged.

According to a feature of the invention, the said locking member of the locking lever that controls the printing member is controlled or supervised by a safety member which, when the machine is ready for working, takes up such a position that it releases 20 the said locking member for releasing the printing member, but can be set in such a 25 position by various parts of the machine that it prevents the locking member from releasing the locking lever.

According to another feature of the invention, the locking member is constituted by a 30 lever that can take up two positions and be held therein by a spring, which lever has two stops or abutments spaced apart, between which the clutch-controller lever aforesaid of the printing member extends with 35 play, one of which stops controls the clutch-operating lever, and the other serves for throwing over the locking member out of its rest position into its locking position by the clutch-operating lever when the latter is 40 moved out of its engaging position into its disengaging position for throwing out the clutch and stopping the printing member.

According to a further feature of the invention when the printing member is formed 45 as a horizontal hollow cylinder the locking lever is mounted to rock on the end of the cylinder in a plane lying transversely of the direction of length of the latter, and the locking member is mounted to rock in a plane 50

extending in the direction of length of the cylinder.

According to yet another feature of the invention, in order to throw over the locking member out of its locking position into its 55 rest or normal position for releasing the locking lever, there is arranged beside the printing cylinder a longitudinally displaceable rod that is parallel with the cylinder, the releasing movement of which rod is transmitted to the locking member by means of 60 a spring.

According to a still further feature of the invention, the safety member aforesaid supervising the locking member is a lever fast 65 on a shaft that lies transversely of the printing cylinder, which shaft carries a second lever in the range of an arm that extends out of the periphery of the printing cylinder and is fast on a rod that is displaceable end- 70 wise in the cylinder, so that by shifting this rod endwise the safety member can be set in its holding or supervisory position.

Other features of the invention relating 75 to the inking device and to the safety member will be described hereinafter and pointed out in the claims.

One embodiment of the invention is diagrammatically illustrated by way of example in the accompanying drawing, wherein: 80

Figure 1 is a plan view of one form of arresting and releasing device according to the invention applied to a machine for stamping or printing postage having a horizontal cylinder, of which machine, however, some parts 85 are omitted and only those requisite for understanding the invention are illustrated;

Figure 2 is a side sectional elevation taken on the line II—II in Figure 1 showing part 90 of the arresting and releasing device.

Figures 3 and 4 are like views of the same parts but in other positions.

Figures 5 and 6 are end sectional elevations taken on the line V—V in Figure 1 showing parts of the device in two different positions, 95 and

Figure 7 is an end sectional elevation taken on the line VII—VII in Figure 1.

Referring to the drawing, a horizontal hollow printing cylinder 1, closed at its ends 100

by end covers 2 and 3, rests near the middle in a ring 4 of the machine frame and has an end pivot 5 journaled in a bearing 6. A worm wheel 7 to be driven by a motor, and a 5 clutch element 8 in the form of a wheel rigidly connected therewith are free to rotate on the pivot 5. A locking disc 9 is mounted on the pivot 5 beside the clutch wheel 8, and between this disc 9 and the end cover 2 is situated a safety disc 13 which is connected by an arm 10 to a pivot 11 on a bracket 12 and is thus held stationary.

A coupling member 15 in the form of a curved pawl is pivoted at 14 to the locking disc 9, and is pressed by spring 16 into the clutch wheel 8. In its engaged position the free end of the pawl 15 extends in the circumferential direction of the wheel 8 somewhat beyond a locking tooth 9' (Fig. 6) on the locking disc 9. A locking lever 18 pivoted at 17 has a broad tooth 18' which controls the pawl 15 and disc 9. This lever 18 is normally held by a spring 19 out of the range of the pawl 15 and disc 9.

25 An arm 20 of the lever 18 spaced away from the cylinder 1 extends into the range of a lug or projection 21 of a cam 22 on the cylinder 1. At each revolution of the printing cylinder in the direction of the 30 arrow shown in Figure 5, the locking lever 18 is moved inwards by means of this cam 21, 22 directly in front of the coupling pawl 15 and the locking tooth 9' against the action of the spring 19, whereby the pawl 15 35 first coacts with the lever 18 and is disengaged from the wheel 8, so that the drive of the printing cylinder is disconnected. Shortly afterwards the tooth 9' coacts with the lever 18, 18', whereby the cylinder 1 is 40 stopped (Fig. 5).

The locking lever 18 is provided on the free end of its arm extending below the disc 9 with a downwardly directed extension piece 18'' that lies in the range of a locking member 24 in the form of a bell-crank lever fulcrumed at 23 to rock in a plane parallel with the longitudinal axis of the printing cylinder. This member 24 can rock between two stops 25 and 26 and is held in one or 45 other end position by a spring 27 that is attached at one end to the upper end of the vertical arm of the lever 24 and has its lower end anchored to a pin 28 fixed in the vertical plane containing the axis of the pivot 23. 50 The upwardly directed or vertical arm of the lever 24 has a lug 29 which in the locking position shown in Figures 2 and 4 engages the lever 18 and holds it in its locking position in which the cylinder 1 is held against 55 rotation.

In order to throw over the locking member 24 out of its locking position into its releasing or disengaged position shown in Figure 3, for instance by means of a letter or the 60 like to be stamped or printed, a disengaging

rod 31 movable endwise in the frame of the counting mechanism is arranged lying against a leaf-spring 30 mounted on the locking member 24, which rod 31 has a disc-shaped head 32 constituting a stop for the 70 letter or the like to be printed.

The horizontal arm of the lever 24 has within reach of the extension piece 18'' of the lever 18 a pin 33, against which the bevelled part 18'' strikes when the lever 18 is 75 thrown over from its releasing position (Figure 6) into its locking position (Figure 5) whereby the lever 24 is also thrown over from its releasing position into its locking position.

80 Provision is made to prevent rotation of the printing cylinder and the consequent production of an uncounted, unrecorded or unauthorized impression when the machine is not ready for operation for any reason, for 85 example when the maximum amount has been reached by the counting mechanism, i. e., the counter must be reset, or when the inking mechanism is inoperative, or when the printing types in the printing cylinder are not 90 correctly set. For this last purpose, a safety or supervisory lever 36 is arranged beside the lever 24 on a shaft 35 that is journaled in two bearings 34 and lies transversely of the cylinder 1, which supervisory lever 36 95 in its normal position shown in Figures 2 and 3 has its lower end lying behind a lateral lug 24' of the horizontal arm of the lever 24 and therefore permits this lug to move up and down. If the machine is out of order 100 or is not ready for working then the lever 36 is in its locking or supervisory position shown in Figure 4 in which its lower end lies over the lug 24'.

105 The safety lever 36 can be set in this operative locking position by means of any one of several endwise movable rods. Within the cylinder 1 is situated a rod 37 which has one end guided to move longitudinally in the end cover 2, and has its other end forced by a spring 38 into a recess 39 in the end cover 3 and is consequently held therein. The front end of the rod 37 is rigidly connected by an arm 40 with a knob or a presser 41 that extends through a handle 42 movable in the cover plate 3. This handle 42 is pivotally connected with bars 43 extending endwise in the cylinder 1, and types, not shown, arranged in rows are movable along and transversely of these bars 43. The said types can be moved and be adjusted relatively to a printing aperture 44 in the periphery of the cylinder only when the rod 37 has been moved out of the recess 39 and has been 115 shifted transversely relatively thereto. To do this the rod 37 must be moved by the press-button 41 against the action of the spring 38. The least movement of the rod 37 towards the rear, however, sends its rear end into a 120 125

hole 45 in the safety disc 13 and thus locks the printing cylinder against rotation.

For doubly securing the printing cylinder against unauthorized rotation thereof, the endwise movement of the rod 37 is transmitted to the shaft 35 and to the safety lever 36 by an arm 46 that extends from the rod 37 laterally out of the cylinder and coacts with an arm 47 fast on the shaft 35, whereby the safety lever 36 is moved from its normal inoperative or rest position shown in Figures 2 and 3 into its operative locking position shown in Figure 4.

The upper end of the safety lever 36 lies against a rod 49 which is movable endwise in the frame 48 of the counting mechanism and normally extends into a hole 52 in a disc 53 (Figs. 1 and 7) under the action of a forked spring 51 engaging an annular groove 50 in the rod 49; this disc 53 is fast on a rotatable hinge pin 54 of a hinged ink-mechanism cover 55 which normally closes part of the upper half of the printing cylinder. When it is desired to open the cover 55 the rod 49 must be pushed out of the disc 53 by pressing on a knob 56 on the spring 51. The rod 49 then moves out of the disc 53, releases the pin of the cover 55 and strikes against the safety lever 36 which secures the locking member 24 in its locking position. When the cover 55 is opened the disc 53 rotates and, when the spring 51 is released, prevents the rod 49 and the safety lever 36 from returning into their normal position shown in Figures 2 and 3. When the cover 55 is closed the disc 53 returns into its original position and permits the rod 49 to enter into the hole 52, which rod then at once releases the safety lever 36 which returns automatically into its normal position.

The machine is also locked by the counting mechanism 57 indicated only diagrammatically in Figure 1 when the maximum amount paid in advance to the post office is used up, to which amount the counting mechanism is set in the usual manner. Normally, a lever 64 that is pressed by a spring 62 against the safety lever 36 and is rotatable about a vertical pivot 63 is prevented from rocking the lever 36 out of its normal position into its locking position, shown in Figure 4, by means of a lever 59 fast on a shaft 58, and a rod 60 that has one end pivoted to the lever 59 and its other end passed through a guide 61. As soon as the shaft 58 is so rotated by the counting mechanism that the rod 60 releases the lever 64, the latter strikes against the safety lever 36 and moves it out of its normal position into its locking position. It is then necessary, by paying the maximum sum set on the counting mechanism to the post office, to unlock the machine, for example by inserting a new control strip, not shown, issued by the post office into the counting mechanism and thereby returning the lever 64 into the

position in which it is arrested by the rod 60 and does not influence the safety lever 36.

It will be appreciated from the above that it is not possible to imprint a stamp or mark in an unauthorized manner when the machine is not ready for operation or is otherwise out of order.

I claim:—

1. In a machine of the character described, the combination of a rotary printing member, and a detachable clutch for driving the same, with a lever that controls the clutch and is placed by the printing member, at each revolution of the latter, in a disengaging position wherein it disengages the clutch and thereby stops the printing member, a locking member arranged to hold said lever in said disengaging position, means controlled by an article to be printed for setting the locking member in its releasing position and thereby releasing said lever, and means actuated by said lever for automatically returning the locking member into its locking position when the clutch is being disengaged.

2. In a machine of the character described, the combination of a rotary printing member, and a detachable clutch for driving the same, with a lever that controls the clutch and is so controlled by the printing member, at each revolution of the latter, that it is placed in a disengaging position wherein it disengages the clutch and thereby stops the printing member, a locking member arranged to hold said lever in said disengaging position, means controlled by an article to be printed for releasing said locking member from said lever, means actuated by said lever for automatically returning the locking member into locking engagement with said lever when the clutch is being disengaged, a safety member for controlling said locking member, and means for controlling said safety member and thereby holding the same in locking engagement with, and releasing it from the locking member.

3. In a machine of the character described, the combination of a rotary printing member, and a detachable clutch for driving the same, with a clutch lever that controls the clutch and is so controlled by the printing member, at each revolution of the latter, that it is placed in a disengaging position wherein it disengages the clutch and thereby stops the printing member, a locking member in the form of a lever movable into two end positions, a spring for holding the locking member in either of said end positions, which locking member has two stops spaced apart, between which stops said clutch lever extends with play and is controlled by one of them, and the other serves for throwing over the locking member out of one end position into its locking position when the clutch lever moves from its engaging into its disengaging position and means controlled by an article to

be printed for releasing the locking member from the clutch lever.

4. In a machine of the character described, the combination of a horizontal rotary printing cylinder, a detachable clutch for driving the same, a clutch lever that is mounted to rock on the end of the cylinder in a plane lying transversely of the direction of length of the latter, which lever controls said clutch, means on said cylinder arranged to coact with said clutch lever and so control it, at each revolution of the cylinder, that the lever is placed in a disengaging position wherein it disengages the clutch and thereby stops the cylinder, a locking member that is arranged to rock in a plane extending transversely of the former plane and is arranged to hold said clutch lever in said disengaging position, means controlled by an article to be printed for setting the locking member in its releasing position and thereby releasing said lever, and means actuated by said clutch lever for automatically returning the locking member into its locking position when the clutch is being disengaged.

5. In a machine of the character described, the combination of a horizontal rotary printing cylinder, a detachable clutch for driving the same, a clutch lever that controls the clutch, means on said cylinder arranged to coact with said clutch lever and so control it, at each revolution of the cylinder, that the lever is placed in a disengaging position wherein it disengages the clutch and thereby stops the cylinder, a locking member arranged to hold the clutch lever in said disengaging position, a spring coacting with said locking member, an endwise movable bar mounted parallel with said cylinder and arranged to be shifted endwise by an article to be printed and transmit its movement through said spring to the locking member for releasing the clutch lever, and means actuated by said lever for automatically returning the locking member into its locking position when the clutch is being disengaged.

6. In a machine of the character described, the combination of a horizontal rotary printing cylinder, a detachable clutch for driving the same, a clutch lever that controls the clutch, means on said cylinder arranged to coact with said clutch lever and so control it, at each revolution of the cylinder, that the lever is placed in a disengaging position wherein it disengages the clutch and thereby stops the cylinder, means controlled by an article to be printed for releasing said locking member from said clutch lever, means actuated by said lever for automatically returning the locking member into locking engagement with the clutch lever when the clutch is being disengaged, a shaft that lies transversely of the length of the cylinder, a safety member that is fast on said shaft and controls the locking member, an endwise

movable rod in the cylinder, an arm that is fast on said rod and extends out of the cylinder, and a lever that is fast on said shaft and is arranged to be rocked by said arm, when said rod is moved endwise, and thereby set the safety member in locking engagement with the locking member.

7. In a machine of the character described, the combination of a rotary hollow printing cylinder, a cover portion for a part thereof, a detachable clutch for driving the cylinder, a clutch lever that controls the clutch, means on said cylinder arranged to coact with said clutch lever and so control it, at each revolution of the cylinder, that the lever is placed in a disengaging position wherein it disengages the clutch and thereby stops the cylinder, a locking member arranged to hold the clutch lever in said disengaging position, means controlled by an article to be printed for releasing said locking member from the clutch lever, means actuated by said clutch lever for automatically returning the locking member into locking engagement with the clutch lever when the clutch is being disengaged, a safety member for controlling said locking member, and means controlled by the opening and closing of said cover portion and arranged respectively to hold the safety member in its locking position in relation to the locking member and release it therefrom.

8. In a machine of the character described, the combination of a rotary hollow printing cylinder, a hinged cover portion for a part thereof, a detachable clutch for driving the cylinder, a clutch lever that controls the clutch, means on said cylinder arranged to coact with said clutch lever and so control it, at each revolution of the cylinder, that the lever is placed in a disengaging position wherein it disengages the clutch and thereby stops the cylinder, a locking member arranged to hold the clutch lever in said disengaging position, means controlled by an article to be printed for releasing said locking member from the clutch lever, means actuated by said clutch lever for automatically returning the locking member into locking engagement with the clutch lever when the clutch is being disengaged, a safety member for controlling said locking member, and an endwise movable rod arranged in one end position to lock said cover portion and release the safety member, and in its other end position to unlock the cover portion and hold the safety member in locking engagement with the locking member.

9. In a machine of the character described, the combination of a rotary printing cylinder, a counting mechanism associated therewith, a detachable clutch for driving the cylinder, a clutch lever that controls the clutch, means on said cylinder arranged to coact with said clutch lever and so control it, at each revolution of the cylinder, that the lever is

placed in a disengaging position wherein it disengages the clutch and thereby stops the cylinder, a locking member arranged to hold the clutch lever in said disengaging position, means controlled by an article to be printed for releasing said locking member from the clutch, means actuated by said clutch lever for automatically returning the locking member into locking engagement with the clutch lever when the clutch is being disengaged, a safety member for controlling said locking member, and a spring-controlled lever that tends to place the safety member in locking engagement with the locking member and is normally held in an inoperative position by the counting mechanism.
